United States Patent Office

Des. 208,082
Patented July 11, 1967

208,082

DISPENSER

Gustave F. Falkenberg, Brookfield, Wis., assignor to Dimensional Products, Inc., Milwaukee, Wis., a corporation of Wisconsin

Filed May 5, 1966, Ser. No. 2,173

Term of patent 14 years

(Cl. D94—3)

Fig. 1

Fig. 2

Fig. 3

Fig. 4

FIG. 1 is a view in perspective of a dispenser showing my new design, a syphon tube and cap and a bottle for liquid to be dispensed being shown in broken lines for illustrative purposes only.

FIG. 2 is a front view of the dispenser,

FIG. 3 is a side view thereof, and

FIG. 4 is a top view thereof.

The undisclosed side of the dispenser is a mirror image of the side shown, and the rear is plain in appearance.

I claim:

The ornamental design for a dispenser, as shown and described.
